UNITED STATES PATENT OFFICE.

CHARLES F. BURROUGHS, OF EAST ORANGE, NEW JERSEY.

PRESS WITH DUPLICATE MOLDS.

1,208,090.

Specification of Letters Patent. Patented Dec. 12, 1916.

Application filed May 10, 1915. Serial No. 27,036.

To all whom it may concern:

Be it known that I, CHARLES F. BURROUGHS, a citizen of the United States, residing at 122 Prospect street, East Orange, 5 county of Essex, and State of New Jersey, have invented certain new and useful Improvements in Presses with Duplicate Molds, fully described and represented in the following specification and the accompanying drawings, forming a part of the 10 same.

This invention relates to an improved means of operating duplicate molds alternately in connection with a single pressing-die, the invention being carried out in an upright press having a horizontal press-bed upon which a slide can be mounted to move across the press-bed and provided with mold-carriers near its opposite ends upon 15 which molds can be detachably supported. The slide is movable by hand-gearing, and stops are provided to set the molds alternately below the die.

The invention relates partly to special 25 means of operating an ejector in the center of each mold-carrier so that it may operate in any mold which is applied to such carrier.

The press is provided with a plunger 30 movable to and from the press-bed, the plunger carrying a platen with face transverse to the movement of the plunger, and the die being secured detachably upon the platen so as to be changed when molds of 35 various characters are applied to the mold-carriers.

The plunger and platen require a considerable retracting movement when changing the die or molds, but means is provided for limiting the retracting movement of the 40 platen after each molding operation, to merely permit the lateral sliding of the molds from beneath the die, thus saving much time in the opening and closing of the press and materially increasing its operative 45 capacity.

The invention will be understood by reference to the annexed drawing, in which—

Figure 1 is an elevation of a press provided with the improvements, viewing the 50 end of the slide; Fig. 2 is an elevation of the press viewing the side of the slide; Fig. 3 is a side view of the bed and platen with the die and molds; Fig. 4 is a plan of the bed, slide and molds; and Fig. 5 is a vertical 55 section on line 5—5 in Fig. 3; Fig. 6 is a plan of the platen; Fig. 7 is an elevation of

the cylinder, platen, and pressing-die, with the arms of the cylinder broken off; and Fig. 8 is a plan of the die-carrier with its fluid connection.

The press-bed A is shown supported on legs B, and connected by tie-bars C to a hydraulic cylinder D, in which the plunger E is fitted, and provided with a flat platen F. A return cylinder G is mounted 65 upon the cylinder D, and its ram G' connected by side rods H with the platen F. The head D' of the cylinder D has a notch d' in each side, as shown in Fig. 6, and a washer is laid over each of such notches, 70 as shown in Fig. 7, to sustain a nut, and a rod b is secured in each notch by such nut and extended downwardly along side of the plunger e, and through the platen. These rods have an enlarged body c, the lower 75 end of which act as stops between the head D' and the platen, to restrict or limit its upward movement during the use of the press in molding. (See Fig. 7).

The slide I is fitted movably to a channel 80 I' in the bed A, and is moved therein by a rack d and a pinion e provided with a crank f. The molds J and J' shown upon the top of the slide, are adapted for molding disk records for reproducing sounds, but the invention is not limited to the use of any special kind of molds. Such molds have one feature especially favorable to the use 85 of the present improvements; namely, a very shallow mold cavity, which produces 90 a very thin product in the molded article or disk; and this peculiarity of the molds permits their opening with a very small movement of the press-platen, and the discharge 95 of the product from the mold by a limited movement of an ejector.

In the operation of this apparatus, one mold is withdrawn from beneath the platen by the act of moving the other under the platen, and the product may thus be ejected 100 from one mold and the plastic material supplied thereto for subsequent pressing, while the pressing-die is operating upon the charge in the other mold. This position of the parts is shown in Figs. 1, 3 and 4, 105 where K designates a heat-insulating block attached to the platen F, and k a die-carrier provided with an internal channel h for the circulation of hot or cold fluid, supplied through a flexible connection.

The die itself is shown at j, consisting of a circular plate, held upon the carrier by an 110

annular flange h^2 . The molds J and J' are mounted upon similar carriers K' which are chambered in the same manner, and provided with flexible connections for supplying steam or cold fluid. These two mold-carriers are attached to the slide by screws l, and are provided in the center with ejectors which are actuated by dogs m when the molds are drawn from beneath the die j. Each ejector 10 consists of a tubular plug n fitted to a bore or socket n' extended through the center of the mold-carrier and the slide beneath it, and attached at its lower end to a cross-bar p which extends transversely across the slide. 15 The ends of the cross-bar project from the sides of the slide, and when the slide is pulled across the bed, such ends move over the tops of dogs o, and are pushed upward thereby. The cross-bar passes through a 20 slot p'.

The under sides of the ends, and the tops of the dogs, are sloped so as to gradually force the cross-bar and ejector upward as the slide reaches the end of its movement; 25 thus discharging the product s of the molding operation from the mold when the mold is wholly exposed, as is clearly shown in Fig. 3. The ejector is shown elevated in Fig. 2, and the molded article removed from the 30 mold. Fig. 5 shows the article ejected. The disk records formed in such a mold require a hole in the center, to set it centrally upon the machine where it is used, and such hole is formed by a centering-pin r which is 35 fitted to the bore of the ejector, and projects normally above the top of the ejector. A boss is formed in the center of the mold-carrier to center the mold or pressing die thereon, and the ejector is formed with a 40 shoulder r' which rests normally upon a shoulder n² in the bore n', and sets the top of the ejector flush with the top of the boss u during the molding operation.

The boss is made to be flush with the molding 45 surface of the mold, and the boss and ejector thus form part of the mold bottom during the molding operation; the pin r alone projecting above such bottom, and thereby forming the center-hole in the record. The pin is attached at its bottom to a 50 web r² in the bottom of the slide.

The slide and block K are formed with 55 ventilating passages r². An upper ejector is movable in the center of the die, but is held normally retracted by a spring t², and is projected, when the die is raised from the mold, by a cross-bar t' which at such times contacts with the lower ends c' of the fixed rods b; which ends project below the lower 60 side of the platen for such purpose, as shown in Figs. 3 and 7. The stops c' are arranged to arrest the platen just as the ejector n' is projected.

A clearing-pin w is fitted to the bore of the 65 ejector n', and is provided with a collar to

rest upon a shoulder t² in such bore, and with a spring t⁴ to hold the pin normally projected. The pin w thus extends below the surface of the die when the mold is opened, but is pushed up by the pin r as the mold is closed, and moves outward again when the mold is opened, to eject any material crowded therein.

In operating the apparatus, a charge of the plastic material is placed in the mold J 75 or J', which is set beneath the die j and the material pressed in the mold; which is heated at first, and afterward chilled to harden the product. The other mold is at the same time charged with the requisite material so 80 as to be pressed as soon as the first is finished. The die is then raised by the action of the ram G', which, in such presses, is supplied constantly with fluid under pressure, by pipe h'. The mold thus being opened, the slide is 85 moved to withdraw it and simultaneously set the charged mold beneath the pressing-die. As the mold is withdrawn, its ejector is actuated by the dogs o, and the product s is lifted from the mold, as shown in Fig. 5; so 90 that the operator can remove it before inserting a charge in the mold. By thus charging one mold while the other is pressing, the capacity of the press is substantially doubled.

It will be understood that the centering-pin r is held rigidly upon the slide, and thus pushes the cleaning-pin u upward when the mold is closed and the centering-pin enters the bore of the ejector n'; the ejector n' being retracted by the spring t² 100 at the same time, so that both are in position to eject the product from the mold when completed. When the mold is opened the cleaning-pin is forced outward by the spring t⁴, and cleans out from the bore of 105 the ejector n' any matter forced therein.

To set the molds centrally beneath the die, stops v are projected upward from the corners of the mold-carriers K', in a manner to engage the shoulder on the outer corner of the die j, and arrest each mold when exactly beneath the die.

To expedite the molding operation, it is desirable to heat and cool the molds as rapidly as possible, and special means is 110 provided to effect that object; the chamber in the mold carrier having a hub in the center, from which a radial partition v' is extended to the side of the carrier through which the heating and cooling fluid are 115 introduced; and the inlet l and outlet l' are connected with the chamber at opposite sides of the partition, so that the fluid must make a circuit through the entire chamber before it can escape.

To promote the rapid circulation of the fluid, three ports w are extended from the chamber for the entering fluid, and three ports w' for its escape, and a header x is fitted to the six ports, and provided with in- 120

let and exit pipes l and l' for flexible connections. The header is divided internally, and the fluid entering at l must therefore pass through the ports w and the circuit of the chamber, to reach the outlet l' .

From the above description it will be understood that all the operations are automatic, when the mold is centered beneath the die after the charge is placed in the mold, as the downward movement of the platen lowers the ejector during the molding operation and raises it when the mold is moved from beneath the die; and the operator's attention may therefore be given entirely to the filling of the molds, and the removal of the finished product. Suitable cocks are in practice connected to the pipes l and l' , as well as to pipes h' and h^2 from the hydraulic cylinders, but they are not shown, as their use is already well known.

Having thus set forth the nature of the invention what is claimed herein is:

1. An upright press having a horizontal press-bed, a slide movable across the press-bed, mold-carriers mounted upon the slide near its opposite ends, an ejector fitted movably to a bore in the center of each mold-carrier, lifting means upon the mold-carrier for moving the ejector upwardly, a plunger movable to and from the press-bed and provided with a platen having a die adapted to coöperate with either of the said molds, and means attached to the press-bed near its opposite ends adapted to operate automatically upon such lifting means to raise the ejector and discharge the article from

the mold, when the carrier is moved into either of its opposite positions.

2. An upright press having a horizontal press-bed, a slide movable across the press-bed, mold-carriers mounted upon the slide near its opposite ends, an ejector fitted movably to a bore in the center of each mold-carrier, the slide having a transverse slot intersecting the bore for the ejector, a cross-bar movable vertically in the slot, means upon the press-bed operating to lift the cross-bar near the ends of the slide's movement to operate the ejector at such time, and a plunger movable to and from the press-bed and provided with a platen having a die attached removably thereto and adapted to coöperate with either of the said molds when moved beneath such die.

3. An upright press having a horizontal press-bed, a plunger having a platen with die carried thereby and movable to and from the press-bed, a slide movable across the press-bed, mold-carriers and molds mounted upon the slide near the ends, manual means to shift the slide with either mold beneath the die, the plunger having a lifting movement sufficient to separate the die widely from the said mold, fixed bolts extended by the side of the platen, and tubular stops fitted removably to the bolts to limit the upward movement of the platen and the resulting movement of the molds.

In testimony whereof I have hereunto set my hand.

CHARLES F. BURROUGHS.
